MAN'S UNDERGARMENT

Rothermel Wise, Lancaster, Pa.

Application March 7, 1946, Serial No. 652,551

3 Claims. (Cl. 2-234)

1

This invention relates to new and useful improvements in men's undergarments and more particularly to that type of undergarment known as "athletic shorts."

An object of this invention is to produce an undergarment having an improved buttonless fly opening which is particularly applicable for snug fitting garments, as it will not gap open.

A further object of the invention is to provide a fly structure having a minimum overlap in order to facilitate use of the garment by the wearer. A still further object is to provide an undergarment with a reenforced area to limit stretching of the garment in a direction parallel to the elastic band secured to the top of the garment, such reenforced area serving to prevent the fly opening from gaping regardless of the position of the wearer when seated or when walking or bending.

At the present time, men's athletic shorts are provided with fly openings between overlapping parts having free edges. With such arrangement it is difficult, particularly in close fitting garments, to form the parts defining the opening in such manner that they will not separate as a result of sagging or becoming stretched, particularly when the wearer is seated, bending, or striding. To overcome that objectionable feature, the parts have heretofore been commonly constructed with a wide overlap which is inconvenient in use for obvious reasons and, as a result of the wide overlap, the distortion of the parts required when the opening is to be used is so great as to cause discomfort to the wearer, as a result of the garment binding and cutting into his body. The usual result is that a compromise construction is adopted in which the parts of the fly may be separated without too much discomfort, but when the opening is not in use, the parts defining it do not lie snugly in place and, consequently, they detract from the appearance of the garment and are uncomfortable to the wearer.

The present invention is, accordingly, directed to the provision of a garment of the type described which includes a fly of novel construction and, in the new garment, the parts of the fly lie in proper position without gaping or binding and the garment thus has a trim appearance. The parts, however, may be readily separated to provide the desired opening and they are so constructed that they yield freely for this purpose. The fly opening can thus be employed without discomfort and after such use, the parts immediately assume and remain in their original trim positions.

2

The desired results are obtained in the new garment by providing a narrow overlap on the fly opening and providing adequate reenforcing in the area in which the fly is located to hold the fly area against lateral displacement to any substantial extent which would result in gaping. Such a construction is obtained by providing a piece of relatively inelastic tape or other reinforcement across the entire front of the garment immediately above the fly opening and another strip of relatively inelastic tape or similar reinforcement across the garment immediately below the fly opening. These two inelastic bands extending substantially horizontally across the full width of the garment prevent it from stretching laterally in the vicinity of the fly.

For a better understanding of the invention, reference may be had to the accompanying drawings in which:

20 Fig. 1 is a front elevational view of a pair of shorts without leg coverings embodying my invention;

Fig. 2 is a similar view of a pair of shorts having leg covering portions;

25 Fig. 3 is a sectional view taken on the line 3-3 of Fig. 1 showing the fly overlap;

Fig. 4 is a front elevational view showing a modification of the invention; and

Fig. 5 is a front elevational view showing a still 30 further modification of the invention.

Referring to Fig. 1 there is shown a conventional pair of "athletic" type shorts comprising a front panel 2 made of knitted fabric having its wales running vertically thereby rendering it capable of stretching readily in a direction parallel to the length of the elastic band 3 attached to the top of the garment, but it is not capable of stretching to any substantial extent in a direction perpendicular to the length of the elastic 40 band 3. This front panel extends from the waistline substantially to the groin line of the garment and from side to side thereof. Below the front panel 2 are two intermediate panels 4 and 5 extending from the groin line downwardly to and 45 terminating just above the crotch. The wales of these intermediate panels may be disposed either in a vertical or horizontal direction. A lower crotch panel 6 is also provided.

The intermediate panels 4 and 5 are formed of 50 two thicknesses of fabric and the panels define a fly construction generally indicated at 7. As shown in Fig. 3, the fly opening is made up of a piece of tubular fabric 8 stitched to the double thickness of fabric constituting intermediate 55 panel 4 and a similar piece of tubular fabric 9.

which is stitched to the intermediate panel 5. The tubular fabric portions 8 and 9 are in overlapping relationship and constitute the whole overlap of the garment at the fly. It will be obvious that with such construction the garment will be more convenient and comfortable.

Since the upper panel 2 is capable of stretch in a direction parallel to the elastic band 3, and this is necessary to insure proper fitting of the garment, means must be provided for preventing such stretch in the zone of the fly opening 7 if gaping is to be avoided. This may be accomplished in a number of different ways. In the preferred embodiment a reenforcing piece 10 is provided which joins the front panel 2 and the intermediate panels 4 and 5. This reenforcing piece 10 is stitched to the panels 2, 4 and 5 after the tubular fabric pieces 8 and 9 defining the fly opening have been stitched to the panels 4 and 5 respectively, so that it is attached not only to such panels but also the fabric members 8 and 9 defining the fly opening 7. The reenforcing piece 10 may be formed of tubular fabric similar to the pieces 8 and 9. In any event it must be of some material which will not stretch appreciably in the direction of the arrow C-C. In place of tubular fabric, the reenforcing may be made of bias tape or other material which is substantially inextensible in a lengthwise direction.

The lower ends of the panels 4 and 5 are bound against stretch by a reenforcing piece 11 which joins the intermediate panels 4 and 5 and the crotch panel 6, being stitched to all three pieces 4, 5 and 6 after the tubular pieces 8 and 9 have been stitched to the panels 4 and 5 respectively. This reenforcing piece is also secured to the ends of the fabric members 8 and 9. The reenforcing 11 may be the same as the reenforcing 10.

From the foregoing it will be observed that the fly opening is bounded above and below by reinforcements which will not stretch to any substantial extent and which serve to hold the panels 4 and 5 against lateral distortion which would result in gaping of the fly opening. It will be noted also that the reenforcing elements extend to substantially the ends of the panels 4 and 5 and in the case of the element 10 it connects with the side seams 12 and 13, while in the case of element 11 it connects with the leg bands 14 and 15 to hold or box-in the fly portion of the garment. Any lateral stretch which might result in gaping is thus effectively inhibited, for the intermediate panels 4 and 5 which are formed into the fly opening at 7 are bounded along both upper and lower edges by the reinforcements 10 and 11 and the fly defining members 8 and 9 are also secured to the reinforcements.

In Fig. 2 a similar construction is shown except that instead of leg bands 14 and 15, the garment is provided with leg cover portions 16 and 17. It will be noted that in this construction the reenforcing piece 11 as well as the reenforcing piece 10 is extended to the side seams 12 and 13 of the garment and thus, like the construction of Fig. 1, prevent stretch in the fly opening area.

In the modified embodiment shown in Fig. 4, a relatively wide band of stitches indicated at 18 and 19 replace the reenforcing fabric 10 and 11. The bands of stitches are in the same areas as the pieces 10 and 11 and serve to prevent the garment from stretching. This may be accomplished by use of a "Merrow" type sewing machine of the nine needle type set to stitch a pattern such as shown in Fig. 4 and provide a reenforcement

which will prevent any substantial lateral stretching of the intermediate panels which would result in gaping at the fly opening.

Fig. 5 shows a further modification in which the intermediate panels 4 and 5 are disposed in such a manner as to have the direction of the wales running horizontally instead of vertically. This structure also prevents lateral stretching in the area of the fly since the knitted material of which the garment is made is substantially inelastic in the direction parallel to the direction of the wales. In this type structure it is not necessary to use the reenforcing members 10 and 11 or the stitched bands 18 and 19; however, these may be used for decorative purposes. I have shown a simple zig-zag type of stitching for joining the intermediate panels 4 and 5 to the front panel and the crotch panel. This type of stitching is commonly used for seaming.

In the embodiment shown in Fig. 5, the panels 4 and 5 do not have to be made of the knitted material commonly used in this type garment, but may be made of any type inelastic material which would serve to prevent stretching in the area of the fly. It is preferred of course to have the whole garment formed of knitted fabric as shown in the various views.

In all forms of this garment the fly overlap is small, being only the width of the tubing 8 and 9, generally about one inch, but the garment is so constructed as to prevent lateral stretching in the area of the fly, thereby preventing the fly from gaping. At the same time, the fly may be employed for its intended purpose without difficulty, since the overlap is slight.

While I have illustrated and described certain preferred embodiments of the invention it will be understood that the invention is not so limited but may be practiced within the scope of the following claims.

I claim:

1. An undergarment composed of knitted material comprising a composite front panel having upper, intermediate and lower sections, the upper and intermediate sections extending from side to side, the said upper section extending from the waistline to substantially the groin line of the garment and from side to side thereof, the intermediate section extending from said groin line downwardly to and terminating just above the crotch, said intermediate section comprising two panels overlapping each other at the center of the garment and forming a fly opening, the lower section being attached to the lower edge of the intermediate section and forming the front of the crotch portion of the garment, said upper section having its wales running in a vertical direction to provide horizontal stretch of the garment, and relatively inelastic means connecting the upper and intermediate sections and the intermediate and lower sections and extending across the garment from side to side thereof.

2. An undergarment composed of knitted material comprising a composite front panel having upper, intermediate and lower sections, the upper and intermediate sections extending from side to side, the said upper section extending from the waistline to substantially the groin line of the garment and from side to side thereof, the intermediate section extending from said groin line downwardly to and terminating just above the crotch, said intermediate section comprising two panels overlapping each other at the center of the garment and forming a fly opening, the lower section being attached to the lower edge of the

intermediate section and forming the front of the crotch portion of the garment, said upper section having its wales running in a vertical direction to provide horizontal stretch of the garment, said intermediate section having its wales running in a vertical direction, and relatively inelastic means connecting the upper and intermediate sections and the intermediate and lower sections and extending across the garment from side to side thereof.

3. An undergarment composed of knitted material comprising a composite front panel having upper, intermediate and lower sections, the upper and intermediate sections extending from side to side, the said upper section extending from the 15 waistline to substantially the groin line of the garment and from side to side thereof, the intermediate section extending from said groin line downwardly to and terminating just above the crotch, said intermediate section comprising two 20 panels overlapping each other at the center of the garment and forming a fly opening, the lower section being attached to the lower edge of the

intermediate section and forming the front of the crotch portion of the garment, said upper section having its wales running in a vertical direction to provide horizontal stretch of the garment, said 5 intermediate section having its wales running in a horizontal direction, and means connecting the upper and intermediate sections and the intermediate and lower sections and extending across the garment from side to side thereof.
